UNITED STATES PATENT OFFICE.

THOMAS H. BELL, JOHN J. HESLIN, AND THOMAS F. DELANEY, OF NEW YORK, N. Y., AS
SIGNORS TO THE DE LANEY HESLIN PRODUCTS CORPORATION, OF NEW YORK,
N. Y., A CORPORATION OF NEW YORK.

TORCH.

Application filed September 5, 1923. Serial No. 661,088.

To all whom it may concern:

Be it known that THOMAS H. BELL, JOHN J. HESLIN, and THOMAS F. DELANEY, citizens of the United States, residing at New York, in the county of New York and State of New York, have invented certain new and useful Improvements in Torches, of which the following is a specification.

Our invention relates to improvements in torches especially adapted for use in soldering, brazing, annealing and other similar work.

The primary object of the invention is to provide a torch having a relative large vaporizing chamber designed so the fuel oil will be superheated prior to being discharged, so as to render the fuel highly combustible to produce a strong hot flame.

A further object of the invention is to provide a vaporizing chamber which may be easily cleaned.

A further object of the invention is to provide a torch having a tool adjustably associated therewith and capable of being moved to lie in the path of the flame whereby it can be conveniently heated.

Another object of the invention is to provide a device of the above-mentioned character which is simple and durable in construction, reliable and efficient in operation, convenient to handle and inexpensive to manufacture.

Other objects and advantages of the invention will be apparent during the course of the following description.

In the accompanying drawing forming a part of this specification and in which like numerals are employed to designate like parts throughout the same,

Figure 1, is a perspective view of our invention,

Figure 2, is a fragmentary longitudinal sectional view of the same, and,

Figure 3, is a plan view, partly in section, showing the vaporizing chamber.

In the drawing, wherein for the purpose of illustration we have shown a preferred embodiment of our invention, the numerals 5 and 6, designate parallel tubular containers closed at their lower ends by screw caps

7, which are removable to permit the replacement of wicks 8 and replenishing of the fuel oil 9, shown more clearly in Fig. 2. The container 6 is shorter in length than the

container 5 and is provided with an elbow discharge pipe 10 rigidly connected to the upper end thereof by the flange 11.

Oppositely disposed tubular extensions 13, project laterally from the horizontal portion of the elbow pipe 10, adjacent the end thereof, forming a substantially cross-shaped vaporizing chamber 12. The open ends of the extensions 13 are closed by air tight screw plugs 14 which may be removed for cleaning the chamber 12. The free end of the discharge pipe 10 is closed by the screw plug 15, apertured through its center to provide an orifice 16 for the discharge of the vaporized fuel.

The fuel oil 9, in the container 6, is introduced into the vaporizing chamber 12, by capillary attraction, through the wick 8, which extends into the discharge pipe 10 but terminates short of the vaporizing chamber.

The upper end 14' of the container 5 is open and the open end is disposed directly beneath the vaporizing chamber 12 of the discharge pipe 10, in close proximity thereto. This container acts as a heating element, and when in use the wick is lighted to supply heat for vaporizing the fuel oil within the chamber 12, and render it highly combustible for discharge through the orifice 16.

A suitable handle 17, substantially U-shape is connected to the torch by bands 18 encircling the container 6. The container 5 carries a collar 19 having a vertical web 20, which unites the two containers and properly spaces them apart.

A tool for use in connection with the torch is associated therewith, and consists of a slidable collar 21, mounted on the container 5, having a laterally extending arm 22 bent upwardly at its outer end. The free end of the arm 22 is forked, as at 23, and supports a hollow wedged shape soldering iron 24, open at one end and provided at its pointed end with small vent openings 25. The tool can be relatively adjusted by the set screw 26 and may be positioned so the opened end of the iron will be directly in the path of the flame from the torch, whereby it may be quickly and easily heated.

It is to be understood that the form of our invention herewith shown and described, is to be taken as a preferred example of the same, and that certain changes in the shape,

size, and arrangement of parts may be resorted to without departing from the spirit of the invention or the scope of the subjoined claims.

5 Having thus described our invention, we claim:

- 10 1. A device of the character described comprising a fuel container, a second container acting as a heating element, a discharge pipe joined to the upper end of the first mentioned container and disposed on a horizontal plane in close proximity to said heating element, and horizontal extensions radiating from said discharge pipe near its 15 end, forming a vaporizing chamber in alignment with said heating element.
- 20 2. A device of the character described comprising a pair of containers, a discharge pipe joined to one of the containers having a horizontal portion overhanging the other container, and extensions projecting laterally from said overhanging portion forming a substantially cross-shaped chamber adjacent the end of said discharge pipe.
- 25 3. A device of the character described comprising a pair of containers, a discharge

pipe joined to one of the containers and overhanging the other container, oppositely disposed extensions projecting laterally from the sides of said overhanging portion near 30 the end of the discharge pipe, closed at their outer ends, and an apertured plug covering the open end of said discharged pipe.

4. A device of the character described comprising a fuel container and a second container for a heating element, a discharge pipe joined to said fuel container and having a horizontally disposed portion overhanging said heating element, branch passages extending horizontally from the sides 40 of said discharge pipe adjacent the free end thereof, forming a vaporizing chamber having a relative large heating surface disposed directly above said heating element, and plugs closing the free ends of said passages 45 and discharge pipe, one of said plugs having a discharge orifice.

In testimony whereof we affix our signatures.

THOMAS H. BELL.
JOHN J. HESLIN.
THOMAS F. DELANEY.
